TOY FIGURE

Lenore H. Morgan, 2601 Manor Drive, Midland, Mich.

Filed Apr. 6, 1961, Ser. No. 64,642

Term of patent 14 years

(Cl. D34—2)

FIG. 1 is a front elevation of the toy figure embodying my new design, and

FIG. 2 is a side elevation.

I claim as my invention:

The ornamental design for a toy figure, substantially as shown.
